(57) **CLAIM**

The ornamental design for a carrier for containers, as shown and described.

DESCRIPTION

FIG. 1 is a perspective view of a carrier for containers showing my new design.

FIG. 2 is a left elevation view of the carrier for containers of FIG. 1, the right elevation view is a mirror image.

FIG. 3 is a front elevation view of the carrier for containers of FIG. 1, the rear elevation view is a mirror image.

FIG. 4 is a top plan view of the carrier for containers of FIG. 1.

FIG. 5 is a bottom plan view of the carrier for containers of FIG. 1; and,

FIG. 6 is a plan view of the carrier for containers of FIG. 1 shown in an unfolded configuration.

The broken lines in the drawings represent both portions of the carrier for containers as well as exemplary environmental subject matter of containers. All broken lines in the drawings form no part of the claimed design.
